GARDEN IRRIGATOR

Frank C. Thames, San Antonio, Tex.

Application September 10, 1946, Serial No. 696,002

2 Claims. (Cl. 299—107)

1

My invention relates to a garden and flower bed irrigator.

An important object of the invention is to provide an irrigator for home gardens, flower beds, and the like, which is adapted for use with the ordinary garden hose.

A further object is to provide an irrigator, for use with a garden hose, which permits the full stream from the hose to flow directly and calmly onto the area being irrigated, without damaging the growing plants.

A further object is to provide a garden and flower bed irrigator, which may be conveniently moved from place to place without turning off the water, and without wetting the user of the device.

A still further object of the invention is to provide an irrigator which is simple and practical, relatively inexpensive to manufacture, and which will efficiently irrigate an average home garden.

Other objects and advantages of the invention will be apparent during the course of the following description.

In the accompanying drawings, forming a part of this application, and in which like numerals are employed to designate like parts throughout the same,

Figure 1 is a central vertical longitudinal section through the irrigator embodying my invention, parts in elevation,

Figure 2 is a bottom plan view of the same.

Figure 3 is a central vertical section through the valve and associated elements, parts broken away, and drawn approximately to full scale, and,

Figure 4 is a fragmentary vertical transverse section taken on line 4—4 of Figure 3.

In the drawings, where for the purpose of illustration, is shown a preferred embodiment of my invention, the numeral 5 designates a hollow elongated generally globular container or bulb, preferably formed of glass, but which can be made of any other suitable material. The container or bulb 5 has a preferably flat bottom 6, having an elongated transverse opening or slot 7, extending for substantially the full width of the bottom 6, and located near the nozzle end 8 of the container. Preferably moulded in the nozzle end 8, and located centrally in the same, is an internally screw-threaded bushing or insert 9, for receiving the externally screw-threaded portion of a nozzle 10.

The nozzle 10 is generally tubular, and includes near its longitudinal center a preferably generally spherical valve body portion 11, having

2

an internal valve seating partition or web 12, formed integral with the nozzle. The web 12, has a valve seating opening 13, for receiving a normally open valve element 14, having a travel limiting or stop shoulder 15, for engaging against the upper inner surface of the valve body portion 11, and limiting the opening travel of the valve. The valve element 14 is rigidly secured to the inner end of a valve stem 16, adapted for reciprocation within an upstanding tubular boss or extension 17, formed upon the valve body portion 11. The upper end of the valve stem 16 is forked for providing extensions or ears 18, having aligned elongated openings or slots 19, for receiving a bolt 20, or the like.

The nozzle 10 carries an upstanding extension or post 21, located near the valve body portion 11. Suitably pivotally connected to the upper end of post 21 is the forward pivoted end of a valve closing lever 22, having a handle portion 23, and adapted for swinging vertically above and arranged longitudinally of the nozzle 10. The lever 22 has a transverse opening 24, for receiving the bolt 20, and connecting the lever with the valve stem 16. The lever 22 is further provided with a spring seating recess 25, for seating one end of a suitable coil compression spring 26, the other end of which is seated in a similar recess 27 formed in the nozzle 10.

The outer open end of the nozzle 10 carries an internally screw-threaded coupling element 28, adapted for receiving the externally screw-threaded end of a conventional garden hose.

The operation of the garden irrigator is as follows:

The screw-threaded coupling 28 is connected with a garden hose and the water is turned on. The spring 26 causes the valve element 14 to remain normally open, and the water from the hose passes through the nozzle and into the container or bulb 5. The force of the water from the hose is dissipated when the water strikes the interior surface of the container, at the end opposite to the nozzle 10. The water calmly flows out of the irrigator through the slot 7 and onto the ground to be irrigated. There is no rush of water from the slot 7, which might damage or wash out small garden plants. The slot 7 is placed at the same end of the container or bulb as the nozzle, so that the water flowing through the slot will have had a maximum path of travel within the container for becoming a calm smooth flow.

When it is desired to move the garden irrigator to a new location, it is not necessary to

turn the water off. The user merely grasps the handle portion 23 of the lever 22 and squeezes the same to the dotted position, shown in Figure 3 of the drawings. This closes the normally open valve, stopping the flow of water into the container or bulb 5. The irrigator can now be moved without the user of the same getting wet in the process. As soon as the lever 22 is released, the flow of water into the container or bulb 5 is resumed.

It is to be understood that the form of my invention, herewith shown and described is to be taken as a preferred example of the same, and that various changes in the shape, size and arrangement of parts may be resorted to, without departing from the spirit of my invention, or the scope of the subjoined claims.

Having thus described my invention, what I claim is:

1. A garden irrigator, comprising a hollow container of impervious material including front and rear ends and a flat bottom adapted to rest atop the ground, said bottom being formed with a transverse slot therethrough adjacent said rear end, a nozzle fixed in said rear end and including a discharge end opening into said container forwardly of said slot, and means for connecting said nozzle to a source of water.

2. A garden irrigator, comprising a hollow container of impervious material including front and

rear ends and a flat bottom adapted to rest atop the ground, said bottom being formed with a transverse slot therethrough adjacent said rear end, a nozzle fixed in said rear end and including a discharge end opening into said container forwardly of said slot, said nozzle including a rigid intake end extending rearwardly of said container and providing a carrying handle therefor, and means for connecting said intake end 10 of said nozzle to a supply of water.

FRANK C. THAMES.
